Attorney

UNITED STATES PATENT OFFICE.

MADISON L. SOUTHALL, OF COVINGTON, TENNESSEE.

WASHBOARD.

Application filed April 25, 1921. Serial No. 464,098.

To all whom it may concern:

Be it known that I, MADISON L. SOUTHALL, a citizen of the United States, residing at Covington, in the county of Tipton and State of Tennessee, have invented certain new and useful Improvements in Washboards, of which the following is a specification.

My said invention relates to an improvement in washboards and it is an object thereof to provide a washboard whose ridges are formed by convolutions of a single wire.

Referring to the accompanying drawings which are made a part hereof and on which similar reference characters indicate similar parts,

Figure 1 is a front elevation of my device,

Figure 2 a side elevation, and

Figure 3 a section on line 3—3 of Figure 1.

In the drawings 5 indicates the body of the washboard having integral legs 6 and a top 7 which may be integral or separate as desired. To form the ribs for rubbing the clothes I wrap a wire 8 around and around the body of the board. This wire has one end attached to the board by a screw 9 and the other end attached to the opposite side of the board by a screw 10. The wire is bent at the sides as shown at 11 so that it may run straight across each of the two faces of the washboard thus forming straight ribs. At the middle of the board 35 a row of staples 12 is driven into it at each side, each staple straddling a convolution of the wire. The rows of staples at opposite sides of the board are arranged at slightly different distances from the sides as shown in Figure 3. Preferably each staple is set at an angle to the perpendicular to reduce the tendency to split the board. It will be noted that the board is somewhat oval in

cross section so that the greatest thickness is at the center.

A soap holder which may be made of sheet metal has a body 13 and downwardly extending prongs 14 which may be inserted under the convolutions of the wire and preferably under two or more thereof. This soap holder may be attached to either side of the board or may be entirely removed therefrom as desired.

As will be evident, this board is very simple in construction and can be manufactured at a low cost. It will also be found very durable and efficient in use. Either face may be used equally well thus securing double the service of the ordinary board. By forming the ribs to extend straight across the board I secure the same effect as in washboards of known type.

Having thus fully described my said invention, what I claim as new and desire to secure by Letters Patent, is:

1. A double-faced washboard having a wire wound about the same to form ribs and a soap holder having legs adapted to extend under one or more convolutions of the wire at either side of the board and having a body portion bent away from the board, substantially as set forth.

2. A double-faced washboard having ribs formed of a continuous wire wound thereabout in convolutions extending across both faces, and a soapholder secured to the body of the washboard by some of the convolutions, substantially as set forth.

In witness whereof, I have hereunto set my hand and seal at Covington, Tennessee, this 22d day of April, A. D. nineteen hundred and twenty-one.

MADISON L. SOUTHALL. [L. S.]
